SAFETY CROSSING DEVICE

Fred S. Lalor, Eagle Grove, and Eugene Allen,
Clarion, Iowa

Application April 9, 1938, Serial No. 201,154

2 Claims. (Cl. 246—128)

This invention relates to safety crossing devices and has for the primary object the provision of a device of this character which will provide a clearly visible signal in the form of a manikin or figure movable into and out of signaling position, either manually operated or automatically controlled by a vehicle or railway rolling stock when traversing a given area to warn either motor or pedestrian traffic against entering said area.

With these and other objects in view, this invention consists in certain novel features of construction, combination and arrangement of parts to be hereinafter more fully described and claimed.

For a complete understanding of our invention, reference is to be had to the following description and accompanying drawings, in which

Figure 1 is a vertical sectional view illustrating a safety crossing device constructed in accordance with our invention and showing a wiring diagram therefor.

Figure 2 is a fragmentary vertical sectional view showing the power driven control for the pneumatic operating means of the signal and also the vent means.

Figure 3 is a fragmentary side elevation showing the pneumatic control occupying an open position to admit air pressure to a cylinder of the operating means for the signal.

Figure 4 is a sectional view taken on the line 4—4 of Figure 5.

Figure 5 is a fragmentary sectional view showing the connection between a valve arm and the governor.

Figure 6 is a fragmentary vertical sectional view illustrating a part of the actuating means for the signal.

Figure 7 is a fragmentary vertical sectional view illustrating the positioning of the electric motor employed for opening and closing the valve in an inoperative position.

Figure 8 is a fragmentary view, partly in section, showing gearing employed between the electric motor and the valve arm of the control valve.

Figure 9 is a view similar to Figure 8 showing the gearing unmeshed and prior to returning to valve closing position.

Figure 10 is a fragmentary sectional view showing the valve and its counterbalance weight for moving said valve into off position when the gearing is unmeshed.

Figure 11 is a fragmentary sectional view illustrating a thermostat and heating coil therefor employed to control a vent valve.

Referring in detail to the drawings, the numeral 1 indicates a supporting casing having mounted thereon a hollow post 2 carrying in its upper end a bracket 3 to which is pivoted a signal supporting element 4 equipped at one end with a counterbalanced weight 5 for the purpose of normally maintaining the signal supporting element 4 in non-signaling position. Suitably connected to the other end of the signal supporting element is a figure or manikin 6, 10 representing a traffic officer carrying in one hand a sign plate 7. The figure 6 and sign plate may be illuminated in any suitable manner. If desired, a suitable hand operating means (not shown) may be employed for actuating the signal supporting element into signaling position, or an automatic operating means may be employed and which will be hereinafter more fully described.

Mounted in the post 2 adjacent the casing 1 is a cylinder 8 having mounted therein a piston 9, the stem 10 of which extends through the upper end of the cylinder and the post and has a pin and slot connection 11 with the signal element 4. A cushion spring 12 surrounds the stem and is secured to the upper head of the cylinder for cushioning the movement of the piston as it nears its uppermost position. The upper cylinder head of the cylinder has a vent opening 13 and the lower end has a vent opening 14 controlled by a valve 15. The lower head of the cylinder has connected thereto a pipe 16 leading to an air supply tank 17, the latter being furnished with compressed air in any suitable way such as a compressor 18 driven by an electric motor 19. A control valve 20 is located in the pipe 16 for opening and closing the cylinder 8 to the supply tank. The valve 20 has secured thereto an arm 21 having a pin and slot connection with one end of a governor 22, the other end of the governor being secured to an electric motor 23 and driven thereby. The governor when non-expanded, as shown in Figure 2, positions the valve to close the cylinder 8 to the supply and the governor when expanded, as shown in Figure 3, positions the valve to open the supply tank to the cylinder 8.

Instead of employing the governor 22 for the actuation of the valve 20, a drive 24 may be provided between the electric motor and the valve 50 consisting of a gear 25 suitably journaled and secured to the valve and a gear 26 capable of being moved into and out of mesh with the gear 25 and secured to the armature shaft of the motor. In this instance, the motor is pivotally 55

mounted, as shown at 27, and a spring 28 engages the motor for nominally retaining the motor in a position to mesh the gear 26 with the gear 25. Connected to the motor for tilting the latter to disengage the gear 26 from the gear 25 is a rod 30 having an eye 31 at one end to slidably receive the stem 10 of the piston. A collar 32 is secured to the stem and is adapted to abut the eye for imparting movement to the rod 30 and in turn tilting the motor to disengage the gear 26 from the gear 25 when the piston nears its uppermost position for the purpose of moving the signal element 4 into dotted line position, as shown in Figure 1, or into signalling position. 5 A counterbalance weight 33 is secured to the valve and acts to move said valve into closed position when the gears 26 and 25 are unmeshed, it being understood that the electric motor acts to open the valve while the weight acts to close the valve. 10 The electric motor is connected in an electric circuit 34 and this circuit includes an electrical source 35 and a block 36 of a railroad track. In order that the circuit be closed railroad rolling stock must enter the block, this block taking in the crossing for motor and pedestrian traffic. While we have described this invention for controlling a crossing of a railroad it is to be understood that it may be readily adapted for high- 15 ways wherein the block 36 will be an area through which traffic proceeds and when said traffic is within the block or area completes the circuit 34.

The vent valve 15 is of the needle type form 20 operated by a thermostat which includes a circuit maker and breaker. The thermostat comprises a diaphragm 37 connected to the needle valve and a heating coil 39 electrically connected to the circuit by conductors 39'. The circuit maker and breaker combined with the thermostat consists of a fixed contact 37' and a movable contact 38' operated by the diaphragm. The movable contact 36' may form a part of the needle valve. The diaphragm when under atmospheric temperature opens the valve 15 to 25 bleed the cylinder and to engage the movable contact with the stationary contact. The contacts 37' and 38' are connected in the circuit 34 for opening and closing the latter to the electric motor. 30

In operation, rolling stock entering the block area 36 completes the circuit 34 energizing the heating coil of the thermostat and energizing the electric motor. The motor opens the valve 20 admitting air pressure to the cylinder 8, forcing the piston upwardly and the signal figure 6 into signalling position. The heat from the heating coil actuates the diaphragm seating the valve and trapping the air pressure in the cylinder to 35 retain the signal in signalling position and at the same time disengaging the movable contact 38' from the contact 37', deenergizing the motor so that the valve will be closed by the action of the governor or the weight 33, depending which form 40 of our invention is employed. The heating coil remains energized so long as the rolling stock remains in the block area and becomes deenergized when the rolling stock moves from the block area so that the diaphragm may cool and return 45 to its initial position, opening the vent opening 14 to bleed the cylinder and permit the weight 5 to move the signal figure into non-signalling position. As the rolling stock or vehicle passes from the block area 36 the circuit 34 is opened, 50 deenergizing the electric motor and the thermo-

stat. The thermostat when deenergized contracts and opens the valve 13, exhausting the air from the cylinder, allowing the weight 5 to return the signal element 4 to non-signalling position. The motor 23 stopping its operation, the governor contracts and restores the valve to a closed position, interrupting the flow of air pressure from the source 17 to the cylinder 8. However, when the drive 24 is employed between the valve and the electric motor, the circuit 34 when caused to energize the motor causes an opening of the valve by the gears 26 and 25 being in mesh. As the piston reaches its uppermost position the collar 32 actuates the rod 30 and rocks the motor on its pivot disengaging the gear 26 from the gear 25. As soon as the gear 26 is disengaged from the gear 25, the weight 23 acts to close and interrupt the flow of air pressure from the source to the cylinder. The piston retains its uppermost position until the circuit is broken which permits the thermostat to open the valve 15 and bleed the cylinder. The bleeding of the cylinder permits the signal element 4 to return to non-signalling position and as the piston returns to its lowermost position the collar 32 moving downwardly, permits the spring 28 to pivot the motor and thereby mesh the gears 26 and 25. 10 15 20 25

It will be understood that the control device 30 for our signal may be adapted to control the movement of various other elements other than signals.

We claim:

1. A safety device comprising a supporting post, 35 a signal element pivoted to said post, counterbalance means normally positioning the signal element in non-signalling position, a cylinder carried by said post, a piston operating in said cylinder and connected to the signal element, an air supply means, a pipe connecting said air supply means to the cylinder, a valve for opening and closing said pipe and when open adapted to admit air to the cylinder for action on the piston to position the signal element in signalling 40 position, an electric motor, an electric circuit for 45 said motor and including a block area through which a vehicle traverses and completes said circuit, means connecting said motor to the valve, and electrical means connected in said 50 circuit for normally closing the latter to the motor and for venting the cylinder and adapted to break the circuit to the motor and close the venting of the cylinder after the signal element 55 moves into signalling position by the vehicle entering the block area and to vent said cylinder after the passing of the vehicle from the block area and to restore the circuit to said motor.

2. A safety device comprising a supporting post, 60 a signal element pivoted to said post, counterbalance means normally positioning the signal element in non-signalling position, a cylinder carried by said post, a piston operating in said cylinder and connected to the signal element, an air supply means, a pipe connecting said air supply 65 means to the cylinder, a valve for opening and closing said pipe and when open adapted to admit air to the cylinder for action on the piston to position the signal element in signalling position, an electric motor, an electric circuit for said 70 motor and including a block area through which a vehicle traverses and completes said circuit, means connecting said motor to the valve and adapted to automatically close the valve on the stopping of the motor, a vent valve for said cyl- 75

inder, a thermostat including a diaphragm connected to the vent valve and a heating coil electrically connected to said circuit, movable and non-movable contacts connected in said circuit for controlling the latter to the motor and having the movable contact actuated by the diaphragm and engaging the non-movable contact when said diaphragm is under atmospheric temperature whereby a vehicle entering the block area closes said circuit and energizes the motor to open the first valve for admitting air pressure to the cyl-

inder to position the signal element in signaling position and simultaneously energizes the heating coil to permit the heat therefrom to act on the diaphragm to seat the vent valve and simultaneously disengage the movable contact from the non-movable contact to deenergize the electric motor and permit said means between the first valve and the motor to act to close said first valve. 5
